DAVIT

Alfred W. Coates, Bayonne, N. J., and Robert Wilson, deceased, late of Brooklyn, N. Y., by Emily Wilson, administratrix, Brooklyn, N. Y.

Application June 1, 1938, Serial No. 211,222

5 Claims. (Cl. 9—22)

Our present invention relates to davits, and more particularly to davits designed for marine service although they may be used for hoisting in general as well.

The principal object of our invention is the production of a davit and controlling means wherein the davit arm is actuated largely by gravity, the weight of the boat and its load.

Another object is the production of a davit so designed and controlled as to permit of installations in ships or similar places where space is a considerable factor, and yet which will permit of positive operation even under the most severe conditions imposed by the listing of the ship, storms and the like.

A still further object is the production of a davit of novel design wherein the davit arm is so mounted as to produce a constantly shifting support for the boat during the operation of said davit, the result being a more positive control of the movement of the boat within smaller limits of time and space.

The many additional objects and advantages of our invention will readily be understood by those skilled in the art and particularly after a study of the following specification and the attached drawings wherein:

Figure 1 is an end elevation, partly in section, of one of our davits as mounted upon a ship deck;

Figure 2 a front elevation thereof;

Figure 3 a modification of a davit arm;

Figure 4 a perspective view of a latch for securing the davit arm in its idle position;

Figure 5 a cross section of a boat securing means;

Figure 6 a front elevation thereof;

Figure 7 a front elevation, partly in section, of a winch;

Figure 8 an end view thereof; and

Figure 9 a detailed view of one of the winch clutch members.

Referring to the drawings the numeral 10 indicates, generally, a support which is secured to the deck of a vessel 11, in a position as near the edge thereof as possible. In the form shown the supports are arranged in pairs and each consists of a horizontal member 12, a vertical member 13, and an inclined track member 14. These three members are secured together by bolts, welding or otherwise, and may be formed of channelled or flanged sections of steel, iron or other suitable materials. Spacing members 15 are used at periodic points to hold the paired supports in correct position and alignment.

The davit arm 16, in the form illustrated, is constructed of a pair of steel plates 17 and 18, held in spaced relation to each other by spacing members 19. The davit arm consists of a body portion 20, an arcuate shaped upper end portion 21 and a lower end portion 22 which tapers to a bearing 23. A pivot pin 24, mounted in a bearing 23, pivotally secures the davit arm to a pair of links 25 which are in turn pivotally secured to the horizontal member 12 of the support. The body portion 20 of the davit arm is provided with bearings 26 for the reception of a shaft 27 upon which are mounted a pair of flanged rollers 28 and which at certain stages of the movement 15 of the davit arm engage the inclined track 14 of the support. In Figure 3 we illustrate a modified form of mounting for the rollers 28 wherein a pair of plates 29 are pivotally secured to the davit arm and in which a shaft 27' is mounted 20 and which carries the rollers 28'. A stop 30 is secured between the plates which, when the davit arm swings forward, engages the davit arm and acts as a support therefor. While we have illustrated and described two different forms of 25 davit arms having two sets of rollers for engagement with the track, it is to be understood we may, if desired, use only one set which will always be in contact with the track, the only difference in the operation of the davit arm being in the movement of the davit arm during the initial movement thereof and the corresponding movement of the links 25.

The upper end of the davit arm has mounted upon each side thereof pulleys 31 over which the hoisting cable is trained. A hook 32 in the davit arm is arranged to engage a ball or eyelet 33 carried by a block 34, and to afford a support for the load imposed upon the block when the davit arm is in the stowaway period.

40 The body of the davit arm also carries a pair of rollers 35 rotatably mounted upon a shaft 36 journaled in the davit arm. The rollers 35 are in engagement with the track 14 at certain periods and act both as a load support as well as a guide for the davit arm during the initial period of movement thereof and until the rollers 28 engage the track.

45 In order to securely sustain the life-boat during the idle period or stowaway period, we provide a series of blocks 38 secured to the davit arm 16 and which are designed to conform to the contour of the boat at the point of engagement. We also provide a cable 39, which has at one end a clamp 40 for engagement with the gunwale of 50 the boat, and which is secured at the other end

to an eyelet 41. The eyelet has a threaded shank for engagement with a block 42 carried in one end of a latch 43 pivoted to the upright member 13 of the support. A nut 44 having a handle or crank secured thereto, is threaded over the free end of the eyelet 41 and provides a suitable means for tightening and loosening the tension on the cable 39. The opposite end of the latch 43 is arranged to engage a pivoted loop member 45 carried by the davit arm, and when the cable 39 is tensioned by means of the nut 44 the latch and loop prevent the davit arm and boat from moving.

A cable 46 is provided to control the raising and lowering of the boat and has one end thereof secured to a drum 47 of a suitable power hoist 48. Inasmuch as the hoist will of necessity have to be positioned at different points with respect to the davit arms because of the varied design of superstructures of various ships, the cable 46 as it leaves the hoist will be passed over pulleys or the like (not shown) to a point in the line with the davit arms. From such point it passes up over a pulley 49 mounted upon the upper end of the member 13 of the support, and from there over one of the pulleys 31 to the block 34. From the block it passes over the opposite pulley 31 and down to the upper end of the member 13 where it is secured.

In Figures 7, 8 and 9, of the drawings, we illustrate a preferred form of winch and one particularly adapted to a davit unit of the type disclosed. The drum 47, over which the cable 46 is trained, is mounted upon a shaft 50 which is journaled at each end in a main frame 51 of the winch. A worm gear 52 is mounted upon the shaft 50 and, meshes with a worm 53 secured to one end of a shaft 54 mounted in a bearing 55 secured to the main frame 51. The opposite end of the shaft 54 has mounted thereon a mitre-gear 56 which meshes with a similar gear 57 loosely mounted upon a shaft 58 rotatably mounted in bearings 59 carried by the frame 51. The shaft 58 has its ends projecting through the frame 51 and squared to accommodate a detachable hand crank. Also mounted upon the shaft 58, but keyed thereto, is a clutch member 60 which engages a corresponding clutch member 61 integrally secured to the mitre-gear 57. The clutch members 60 and 61 are machined to allow for a large clearance so as to permit of rotary movement therebetween for a purpose later to be described.

A shaft 62 is mounted in the frame 51 parallel to the shaft 58 and has mounted thereon a gear 63 which is arranged to mesh with a gear 64 mounted upon the shaft 50. Like the shaft 58 the shaft 62 has its ends projecting through the frame 51 and squared for engagement with a detachable hand crank. A gear 65 is mounted upon the shaft 62 which meshes with a gear 66 mounted upon the shaft 58.

An electric motor 67 is mounted in the lower part of the frame and carries a pinion 68 which meshes with the gear 64 carried by the shaft 50.

From the construction just described it will be apparent that we have devised a novel and practical winch which will operate with equal success whether driven by hand or by power. When it is desired to lower the boat, by hand for example, the operator rotates the hand-crank and in turn the shaft 62, or in case he desires a different gear ratio, he places the crank on the end of shaft 58, either of which causes the gear 64 to rotate and also the mitre gears 56 and 57. The rotation of

the shaft 58 and the gear 64 causes the clutch members 60 and 61 to rotate the drum and also the worm wheel 53. If power is used the pinion 68 rotates the gear 64 and the result is the same. It is well known that worms and worm gears may be driven in one direction only. In the design described we employ a worm wheel and worm having such an acute angle between them that no motion of the shaft 50 may be had except in one direction unless the friction on the worm gear is relieved by rotation of the shaft 58 at the same time. When the power on the shaft 50 is removed, the clutch members, because of the play or clearance between their engaging surfaces, break their contact due to the load on the drum, whereupon the worm and worm gear carry the entire load. In view of the acute angle the friction between the two prevents all movement of the drum until power is again applied. This construction prevents all movement of the drum in case the power is interrupted by accident or otherwise.

The block 34 has a link 75 pivotally mounted in the lower portion thereof for forming a detachable connection with the lifeboat. The link 75 is arranged to be projected through a slot in a plate 76 secured in the end of the boat and to be engaged by a pivoted counterbalanced latch member 77 which is connected to one end of a pivoted arm 78. A rope or similar means may be connected to the arm 78 and thereby enable the link 75 to be released from a distant portion of the boat.

In operation our davit operates as follows:

Assuming the boat and its control is in the stowaway position and it is desired to lower the boat, the crew will first rotate the hand crank 44 which releases the tension on the securing cable 39, the winch will next be operated, by power or by hand, which will cause the cable 46 to permit the davit arm to move outwardly. The reason for this movement is due to the weight of the boat and the fact the davit arm is never in a position when gravity will not be effective thereon. The initial movement of the davit arm will be lateral until the links 25 cause the upper part of the davit arm to move faster than the lower end which movement causes the rollers 28 to engage the track 14. At this point the links 25 begin to swing on their pivots which permits the davit arm to continue its outward and downward movement until the free end of the davit arm is projected well out over the edge of the deck. Here the further movement of the arm is arrested whereupon the block leaves the hook 32 of the davit arm and it is lowered to the water line with the boat. At this point the counterbalanced arm 78 may be rotated which releases the link 75 and the boat freed from the mother ship. To raise a boat the operation is reversed.

Thus it will be seen that we have originated and perfected a novel type of davit and a control therefore, wherein the davit arm is of the floating gravity actuated type and which at all times is so flexibly mounted as to permit of great movement and still be under the positive control of the operator. It will also be seen that the construction of our controlling mechanism, and particularly the winch, is novel and particularly adapted to operations of this kind.

While we have illustrated and described certain constructions and combinations it is to be clearly understood that other combinations and constructions may be resorted to without departing from the spirit and scope of our invention.

We claim:

1. A davit structure comprising a support adapted to be positioned adjacent the side of the ship and a davit arm mounted thereon for swinging movement from a generally vertical position to a generally horizontal position; said support including a base element and an element formed to provide an upper track surface secured thereto at an acute angle with respect to the base element whereby it is adapted to slope downwardly and outwardly with respect to the ship's side, said davit arm including upper and lower portions, pivot means adjacent the lower end of the arm, and fulcrum means positioned intermediate the ends of the arm for unconstrained engagement with and movement along the track surface, said pivot means including a link element pivotally attached to the lower end of the davit arm and pivotally attached to the base element approximately midway between the 20 ends of said base element whereby the upper portion of the davit arm may move outwardly and downwardly under the action of gravity, the length of said link element being such that the distance of outward movement is greater than 25 the distance of downward movement.

2. A davit structure as claimed in claim 1 wherein, with the davit arm in vertical position, the upper arm portion is shaped to project outwardly to such a distance that the center of grav- 30

ity of a load supported thereby lies substantially directly over the pivot in said base element.

3. A davit structure as claimed in claim 1 wherein, with the davit arm in vertical position, the upper arm portion is shaped to project outwardly to a point approximately over the pivot in said base element and wherein said link element projects from the pivot in the base element inwardly approximately the same distance that the upper arm portion projects outwardly, whereby with the davit arm in said vertical position it stands substantially entirely to one side of said pivot in the base element.

4. A davit structure as claimed in claim 1 15 wherein the fulcrum means includes track engaging elements spaced transversely of the arm, each engaging only the upper surface of the track whereby they may ride over obstructions on the track in their travel therealong.

5. A davit structure as claimed in claim 1 wherein the fulcrum means includes a bar element pivotally attached to the davit arm and wherein fulcrum elements are pivotally attached to opposite ends of the bar element for rolling engagement with the track.

ALFRED W. COATES.

EMILY WILSON,
